(No Model.)

A. E. STOUT.
BUGGY TOP ATTACHMENT.

No. 566,351.

Patented Aug. 25, 1896.

UNITED STATES PATENT OFFICE.

AMIE E. STOUT, OF AARON, INDIANA, ASSIGNOR OF ONE-HALF TO FRANK W. KAMMANN, OF SAME PLACE.

BUGGY-TOP ATTACHMENT.

SPECIFICATION forming part of Letters Patent No. 566,351, dated August 25, 1896.

Application filed June 16, 1896. Serial No. 595,779. (No model.)

To all whom it may concern:

Be it known that I, AMIE E. STOUT, a citizen of the United States, residing at Aaron, in the county of Switzerland and State of Indiana, have invented a new and useful 5 Buggy-Top Attachment, of which the following is a specification.

My invention relates to buggy-tops, and particularly to an attachment therefor, where- 10 by the operations of raising and lowering are facilitated, to enable the driver to adjust the same quickly and without reaching around the side curtains to break the main brace.

The objects and advantages of this inven- 15 tion will appear in the following description, and the novel features thereof will be particularly pointed out in the appended claim.

In the drawings, Figure 1 is a side view of 20 a buggy-top provided with an operating device constructed in accordance with my invention. Fig. 2 is a detail perspective view of the operating device detached.

Similar numerals of reference indicate corresponding parts in both figures of the drawings.

In the construction illustrated in the drawings the buggy-top is provided with the usual main, front, and rear ribs 1, 2, and 3, said front and rear ribs being attached to the main 30 rib, which is pivoted to the body of the vehicle, and the front rib being pivotally mounted and being held at the desired extension by a jointed front brace 4. The top is held in an upright position by means of the main 35 jointed brace 5, having the main or lower section 5^a and the short or upper section 5^b.

The operating device embodying my invention consists of a rock-shaft 6, mounted in bearing-eyes 7, attached to the main buggy- 40 top rib near its upper end, said shaft being extended outwardly through the side curtain and carrying a crank-arm 8, which is loosely connected, by means of a link 9, with the short upper section 5^b of the main brace. 45 Said rock-shaft is provided between its bearing-points with a curved operating-lever 10, terminating in a handle 11. Said lever is thus arranged inside of the buggy-top, and

it is slightly deflected to allow its free end to pass inside of the main rib, as shown in Fig. 50 2, excessive deflection thereof being prevented by a brace 12, connecting the front and rear ribs of the top.

From the above description it will be seen that the main brace may be either "broken" 55 or "set" by the manipulation of the lever, which is within easy reach of the driver occupying the seat of the vehicle, and hence the top may be adjusted without losing control of the horse, and in case of a runaway, 60 when it is necessary to lower the top quickly in order to give the occupants of the vehicle an opportunity to escape, the same may be readily accomplished.

It will be understood that the mechanism 65 above described is duplicated upon the opposite side of the vehicle.

Various changes in the form, proportion, and the minor details of construction may be resorted to without departing from the spirit 70 or sacrificing any of the advantages of this invention.

Having described my invention, what I claim is—

The combination with a buggy-top having 75 a main brace comprising upper and lower jointed sections, of a rock-shaft mounted in bearing-eyes on the main rib of the buggy-top, said rock-shaft being extended outwardly through the side curtains, a crank-arm carried 80 by the exposed end of the rock-shaft, a pitman connecting the extremity of said crank-arm with the upper section of said main brace contiguous to its joint, and a curved operating-lever attached to the rock-shaft in 85 the plane of the ribs of the buggy-top and having its free end deflected inwardly to swing clear of the inner side of the main rib, substantially as specified.

In testimony that I claim the foregoing as 90 my own I have hereto affixed my signature in the presence of two witnesses.

AMIE E. STOUT.
